METHOD OF MAKING PACKAGES PROVIDED
WITH TEARING STRIPS

Edward F. Cornock, Springfield, Mass., assignor
to Package Machinery Company, Springfield,
Mass., a corporation of Massachusetts

Application December 10, 1940, Serial No. 369,382

9 Claims. (Cl. 93—2)

In the wrapping of articles it is customary to include a tearing strip within the wrapper to facilitate the removal of all or a portion of the wrapper. Where the entire wrapper is to be removed the introduction of the tearing strip is not in general difficult since its location is not critical. In certain cases, however, it is desired to remove only a small fraction of the wrapper to permit access to the contents, and to leave the remainder of the wrapper in place as a protection to the package. If the wrapper is of the usual type which is folded first circumferentially about the article and then into overlying flaps upon the top and bottom of the article there is again slight difficulty in applying the tearing strip, since it can be located as close to the top as desired and still have its end project from between the overlapping ends of the circumferential folds. In the wrapping of articles in so-called die-folded wrappers, however, where the portion of the wrapper to be torn off is one of the folded sides adjacent the final folds, there has previously been no method of so locating the tearing strip as to leave a pouch intact upon the article and at the same time to have the torn line located close to that side of the package which is to be exposed.

In the making of a die-folded package the wrapper is first folded over one side and two adjacent faces of the article, with a sufficient marginal excess of the wrapper projecting beyond two faces to provide material for forming overlapping folds upon the remaining three article sides. The margins of the wrapper are then folded upon the top and bottom of the article, as the two faces adjacent the three initial faces may be called for convenience and without limiting the article to any specific position. The wrapper is finally folded down upon the second side of the article, that is to say the one opposite that with which the wrapper first made contact. It is the purpose of the present invention to locate a tearing strip close to the top of the article, and to fold the wrapper upon the second side so that the exposed end of the tearing strip will not be buried in the folds and will be in a position so that the wrapper may be torn without danger of breaking the tearing strip due to being refolded on an angle among the overlapping flaps of the wrapper. The manner in which this is accomplished can be understood best by reference to the accompanying drawings, in which,

Figs. 1 to 5 are perspective views illustrating successive steps in the wrapping of an article

in accordance with one form of the invention; and

Figs. 6 to 10 inclusive are similar views illustrating successive steps in accordance with a second modification.

Prior to the start of the folding operation a tearing strip 11 is secured to the wrapper 12, preferably in a manner fully described in the patent to Melhorn 1,965,524. In the case illustrated in Figs. 1 to 5 the tearing strip is permitted to extend beyond the wrapper at that side which is to be the first to be folded against the last-closed side of the article, while in Figs. 6 to 10 it projects from the end of the wrapper which is the last to be folded against this side. This makes but minor differences in the performance of the method as will be disclosed below. The tearing strip is adherently secured to the wrapper and projects beyond it as at 13 adjacent this projecting end. The wrapper has a preferably semi-circular notch 14 and generally has a corresponding projection 15 at the opposite end. Regarding this projection the tearing strip is cut along a preferably diagonal line 16 which is located so as to bring the end of the tearing strip adjacent one of the triangular folds to be made later.

With the wrapper and tearing strip thus prepared, the wrapper is brought against one side of the article as in Fig. 1. This will hereinafter be spoken of as the first side. The wrapper is then folded over against the two faces of the article which lie adjacent this side and the marginal portions of the wrapper are folded down with a preliminary tuck 17 and with overlapping folds 18 and 19 as indicated in Fig. 2. The faces against which these folds are made will be referred to as the top and bottom of the article, the former being the one near which the tearing strip is located. These terms are used for convenience and not as limiting the invention to any particular position of the article either during wrapping or in use. This brings the wrapper to a pouch-like form having a tubular extension beyond the second side of the article and with the end 13 of the tearing strip projecting beyond this extension. It should be noted that the marginal excess of the wrapper necessary to produce the flaps 18 and 19 is similar to the marginal excess of the tubular extension necessary to form the flaps against the second side of the article, and to this extent governs the type of flaps which will be formed there. It is one of the features of the present invention that it permits the tearing strip to be located closer to the

top of the article than a distance represented by this marginal extent. In former methods the tearing strip could not be located close to the adjacent side of the article than the width of the flaps to be made against that side last to be closed in.

The next operation is the formation of tucks 28 and 29 against the second side of the article. Tuck 29 may be made as usual, that is to say, the full width of that side of the article; but tuck 28 must be handled in a special manner. The tearing strip projects out through the tubular extension of the wrapper within the space where the triangular connecting flap 22 must lie. This flap is therefore left open, the tuck 28 being separated from the adjacent edge of the article along a slanting line 23, and the flap 22 is left uncreased. The portion of the wrapper extending from the second face of the article is formed into trapezoidal flap formation 24 in the usual way. The trapezoidal flap 25 is folded over first as indicated in Fig. 4, care being taken to exert pressure on the triangular portion 22 in such a manner as to roll it toward the adjacent article corner and thus to bring its folded edge 26 substantially into parallelism therewith. In general the fold 26 will terminate at the edge of the tearing strip. The tearing strip is thus brought up underneath the flap 24 and in order to avoid striking it is preferably folded at right angles to itself along a line 27. When the flap 24 is finally turned down into place the package is in the form shown in Fig. 5. By having the flap 22 rolled outwardly as shown and the opposite corner flap 27' made in the normal manner by folding the tuck 20 tightly against flap 24, the tearing strip will be brought out at a point which is nearer the corner of the article than the slanting flap 27'. This is convenient, as the tearing strip is left free to start a tear without having to be first pulled out from underneath the overlying flap 24.

The operation in the second form of the method is somewhat similar, the tearing strip being attached in substantially the same manner, but in this case a slit 30 is made closely adjacent to it on the outside. A second shorter slit 31 is preferably also made in the wrapper just on the inside of the tearing strip. The length of the slit 30 is of considerable importance as will appear below, and is preferably chosen so as to be less in length by an amount 32 than the distance from the end of the wrapper to the line 33 along which the wrapper is to be folded upon the second end of the article. The operation of folding the wrapper into package form is carried on as before and is illustrated in Fig. 7 with the distinction that in this case the projecting end 34 of the tearing strip is here shown as extending from the opposite side of the package from that indicated in Fig. 2. In the folding of the wrapper against the second end of the article the rolled flap 22 is not employed, the tuck 35 carrying in the entire side portion of the wrapper outside of the slit 30 and laying this against the end of the article with the exception of a small triangular connecting flap 36 that is formed by reason of the distance 32 between the end of the slit and the full line 33. The flap 37 is then folded against the article and finally the flap 38, bringing the article into the condition of Fig. 10. The tearing strip is thus permitted to lie closely adjacent the top of the article by reason of the fact that its end 34 is not buried in any inturned folds of the wrapper since these folds must all

lie outside of the slit 30. In this construction the flap 38 outside of the tearing strip is not anchored as firmly as in the forms shown in Figs. 1 to 5 and for this reason the slit 31 is preferably added, since the tearing strip would otherwise tend to pull the flap 38 away from the inner flap 37 without starting a tear.

In either of the constructions shown the tearing strip is brought close to the adjacent edge 10 of the article and at the same time its projecting portion extends from the body of the strip in a perfectly straight line having no reverse bends which might cause breakage of the strip itself when the package is being opened. While the 15 invention is not limited in its details to the two specific forms shown its general character will be apparent from the following claims.

I claim:

1. A method of forming a wrapped article having a tearing strip located to remove the folded top of the wrapper while leaving the remainder of the wrapper in pouch form on the article, which comprises folding against one side and two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending 20 from both faces of the article with the tuck adjacent the top folded unsymmetrically to bring the lateral outer corner of that flap including the projecting end of the tearing strip outside the tearing strip and to bring the lateral outer corner of the opposite flap inside the line of the tearing strip, and folding and securing said flaps in overlapping relation upon said second side of the article.

2. A method of forming a wrapped article having a tearing strip located to remove the folded top of the wrapper while leaving the remainder of the wrapper in pouch form on the article, which comprises folding against one side and two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the tuck adjacent the top folded unsymmetrically to bring the lateral outer corner of that flap including the projecting end of the tearing strip outside the tearing strip and to bring the lateral outer corner of the opposite

flap inside the line of the tearing strip, folding that flap including the projecting part of the tearing strip against the second side of the article, folding the projecting end of the tearing strip at right angles to itself to cause it to project beyond the top of the article, and folding and securing the opposite flap against the second side of the article in overlapping relation to the first-folded flap.

3. A method of forming a wrapped article having a tearing strip located to remove the folded top of the wrapper while leaving the remainder of the wrapper in pouch form on the article, which comprises folding against one side and two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the tuck adjacent the top folded loosely adjacent the projecting end of the tearing strip and folded tightly adjacent the face opposite thereto, and folding and securing said flaps in overlapping relation upon said second side of the article.

4. A method of forming a wrapped article having a tearing strip located to remove the folded top of the wrapper while leaving the remainder of the wrapper in pouch form on the article, which comprises folding against one side and two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the tuck adjacent the top folded loosely adjacent the projecting end of the tearing strip and folded tightly adjacent the face opposite thereto, folding that flap including the projecting part of the tearing strip against the second side of the article, folding the projecting end of the tearing strip at right angles to itself to cause it to project beyond the top of the article, and folding and securing the opposite flap against the second side of the article in overlapping relation to the first-folded flap.

5. A method of forming a wrapped article having a tearing strip located to remove the folded top of the wrapper while leaving the remainder of the wrapper in pouch form on the article, which comprises folding against one side and

two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the tuck adjacent the top folded loosely on the side adjacent the tearing strip, and folding and securing said flaps in overlapping relation upon said second side of the article while rolling said loosely folded flap towards the top of the article to cause the inner ply of said flap to cross the tearing strip within the boundary of the flap.

6. A method of forming a wrapped article having a tearing strip located to remove the folded top of the wrapper while leaving the remainder of the wrapper in pouch form on the article, which comprises folding against one side and two adjacent faces of an article a wrapper having sufficient marginal excess to form overlapping folds on the opposite side and on the top and bottom of the article, said wrapper having affixed to its inner surface a tearing strip positioned to extend across a first side and the two faces of the article at a distance from the top of the article less than the marginal excess of the wrapper and to project from the first face beyond one end of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the tuck adjacent the top folded loosely adjacent the tearing strip, folding the flap bearing the tearing strip against the second side of the article while rolling said loosely folded flap towards the top of the article to cause the inner ply of said flap to cross the tearing strip within the boundary of the flap, folding the projecting end of the tearing strip at right angles to itself to cause it to project beyond the top of the article, and folding and securing the opposite flap against the second side of the article in overlapping relation to the first-folded flap.

7. A method of forming a wrapped article having a tearing strip located to remove the folded top of the wrapper while leaving the remainder of the wrapper in pouch form on the article, which comprises folding adjacent one side and two adjacent faces of an article a wrapper having sufficient marginal excess to form overlapping folds on the opposite side and on the top and bottom of the article with the excess having a maximum length no greater than the width of said side, top, and bottom, said wrapper having affixed to its inner surface a tearing strip positioned to extend across the first side and the two faces of the article at a distance from the top of the article less than the marginal excess of the wrapper and to project beyond one end

of the wrapper, said wrapper being also formed with a first slit adjacent the projecting end of the tearing strip at one side thereof and between said strip and the adjacent side of the wrapper, said slit extending into the body of the wrapper substantially throughout its marginal excess and also having a second and shorter slit adjacent the projecting end of the tearing strip at the other side thereof and extending into the body of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the portion of the wrapper outside the first slit folded against said side and with a short slanting fold connecting the adjacent flap with the wrapper at the top of the article, and folding and securing said flaps in overlapping relation upon said second side of the article.

8. A method of forming a wrapped article having a tearing strip located to remove the folded top of the wrapper while leaving the remainder of the wrapper in pouch form on the article, which comprises folding adjacent one side and two adjacent faces of an article a wrapper having sufficient marginal excess to form overlapping folds on the opposite side and on the top and bottom of the article with the excess having a maximum length no greater than the width of said side, top, and bottom, said wrapper having affixed to its inner surface a tearing strip positioned to extend across the first side and the two faces of the article at a distance from the top of the article less than the marginal excess of the wrapper and to project beyond one end of the wrapper, said wrapper being also formed with a first slit adjacent the projecting end of the tearing strip at one side thereof and between said strip and the adjacent side of the wrapper, said slit extending into the body of the wrapper substantially but not completely throughout its marginal excess, and also having a second and shorter slit adjacent the projecting end of the tearing strip at the other side thereof and extending into the body of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the portion of the wrapper outside the first slit folded against said side and with a short slanting fold connecting the adjacent flap with the wrapper at the top of the article, and folding and securing said flaps in overlapping relation upon said second side of the article.

sion beyond the second side of the article, tucking those portions of the wrapper extension adjacent the top and bottom of the article against the second side to form opposed flaps extending from both faces of the article with the portion of the wrapper outside the first slit folded against said side and with a short slanting fold connecting the adjacent flap with the wrapper at the top of the article, and folding and securing said flaps in overlapping relation upon said second side of the article.

9. A method of forming a wrapped article having a tearing strip located to remove the folded top of the wrapper while leaving the remainder of the wrapper in pouch form on the article, which comprises folding adjacent one side and two adjacent faces of an article a wrapper having sufficient marginal excess to form overlapping folds on the opposite side and on the top and bottom of the article with the excess having a maximum length no greater than the width of said side, top, and bottom, said wrapper having affixed to its inner surface a tearing strip positioned to extend across the first side and the two faces of the article at a distance from the top of the article less than the marginal excess of the wrapper and to project beyond one end of the wrapper, said wrapper being also formed with a first slit adjacent the projecting end of the tearing strip at one side thereof and between said strip and the adjacent side of the wrapper, said slit extending into the body of the wrapper substantially but not completely throughout its marginal excess and also having a second and shorter slit adjacent the projecting end of the tearing strip at the other side thereof and extending into the body of the wrapper, folding and securing the wrapper in overlapping folds upon the top and bottom of the article and thus forming a tubular wrapper extension beyond the second side of the article, tucking those portions of the wrapper extension adjacent the top and bottom of the article against the second side to form opposed flaps extending from both faces of the article with the portion of the wrapper outside the first slit folded against said side and with a short slanting fold connecting the adjacent flap with the wrapper at the top of the article, and folding that flap not including the projecting part of the tearing strip against the second side of the article, and folding and securing the flap including the projecting part of the tearing strip in overlapping relation to the first-folded flap.

EDWARD F. CORNOCK.
